(57) **CLAIM**

The ornamental design for a magnetic ball marker, as shown and described.

DESCRIPTION

FIG. 1 is a front view of a magnetic ball marker showing my new design;

FIG. 2 is a rear view of the magnetic ball marker;

FIG. 3 is a left side view of the magnetic ball marker, a top view, a bottom view, and a right side view each being identical thereto; and,

FIG. 4 is a top front side perspective view of the magnetic ball marker.

For clarity, the body of the marker is symmetrical and the back face of the marker is planar.
